US00D822212S

(12) **United States Design Patent** (10) Patent No.: **US D822,212 S**
Sebban (45) Date of Patent: ** Jul. 3, 2018

(54) **CONNECTED MINI BLOOD GLUCOSE METER**

(71) Applicant: **VISIOMED GROUP**, Paris (FR)

(72) Inventor: **Eric Sebban**, Paris (FR)

(**) Term: **15 Years**

(21) Appl. No.: **35/502,053**

(22) Filed: **Oct. 20, 2016**

(80) **Hague Agreement Data**

Int. Filing Date: **Oct. 20, 2016**

Int. Reg. No.: **DM/093597**

Int. Reg. Date: **Oct. 20, 2016**

Int. Reg. Pub. Date: **Dec. 9, 2016**

(51) **LOC (11) Cl.** 24-00
 (52) **U.S. Cl.** USPC **D24/169**

(58) **Field of Classification Search**

Primary Examiner — Rhea Shields

(57) **CLAIM**

The ornamental design of a connected mini blood glucose meter, as shown and described.

DESCRIPTION

Reproduction **1.1** is a rear view of a connected mini blood glucose meter showing my new design.

Reproduction **1.2** is a top view thereof.

Reproduction **1.3** is a bottom view thereof.

Reproduction **1.4** is a front view thereof.

Reproduction **1.5** is a left side view thereof.

Reproduction **1.6** is a perspective view thereof.

The broken lines in the drawings are for illustrative purposes only and form no part of the claimed design.

1 Claim, 6 Drawing Sheets
